[57] ABSTRACT

The invention is an electrical circuit for use in a game. It includes a number of multiple pole switches all of which are in series connection with a power source, win indicator and other conventional electric game circuitry. Preferably, a single pole of each switch is connected to the common terminal of the next switch in sequence thus enabling a player to attempt, by setting each switch, to guess the correct combination which will close the circuit and produce a win. Another multiple pole switch may also be provided between the power source and the common terminals of the other switches for the purpose of adding or removing one or more switches from the circuit thus increasing or decreasing the odds against a winning selection.

ELECTRICAL CIRCUIT HAVING AN ODDS SELECTOR FOR A GAME OF CHANCE

CROSS REFERENCES TO RELATED APPLICATIONS

This application is related to Application Ser. No. 304,349 filed on Nov. 7, 1972 by Ken E. Sniderman and Jeffrey Maltby, and now abandoned.

BACKGROUND OF THE INVENTION

Field of the Invention

The invention is an electrical circuit intended for use in a game for home use in which the player must select a correct combination of numbers, objects or the like, in order to win.

SUMMARY OF THE INVENTION

This invention is an electrical circuit for use in a game in which the player must guess a preset combination of numbers, objects or the like. Further, a preferred embodiment of the invention enables the player to select, from several values, the odds against which he wishes to play.

The circuit includes, a multiplicity of switches (secondary selectors) each having a multiple of poles and being wired in sequential order. At least one numbered pole, but fewer than all such poles, on each switch is wired to the common terminal of the next switch in sequence. Thus each switch must be set to the proper position if there is to be a closed electrical path from one switch to the next through the circuit.

Variability of the odds is incorporated into the invention by another switch, referred to as the odds selector, which is also a multiple pole switch. Each numbered pole of the odds selector is connected to the common terminal of one of the previously described secondary selectors. Thus by moving the odds selector to different settings a greater or lesser number of secondary selectors will be included in the circuit thus increasing or decreasing the odds against a winning guess by the player. The odds may also be controlled by varying the number of poles on each secondary selector and by wiring more or less poles on each selector into the circuit.

In order to allow the combination necessary for a win to be changed, as may be appropriate, the electrical connections to the numbered poles are preferably made removable or otherwise changeable. However, the specific means for changing this combination are conventional and not a part of this invention.

The entire circuit of this invention may be included in a conventional electrical game which includes a power source and means for indicating a win.

BRIEF DESCRIPTION OF THE DRAWING

The FIGURE is a schematic circuit diagram illustrating one embodiment of the present invention.

DETAILED DESCRIPTION OF A PREFERRED EMBODIMENT

The particular embodiment chosen for purposes of description is illustrated in the FIGURE, in schematic fashion. The invention is an electrical circuit preferably intended for use in a game of chance.

Multiple pole switches are indicated in dotted fashion at 10, 12, 14, 16 and 18. Switch 10 will be referred to hereinafter as the "odds selector," and switches 12, 14,

16, and 18 will be referred to hereinafter as "secondary selectors." Each of the switches 10, 12, 14, 16 and 18 may comprise any conventional switching mechanism or circuit, or the like, as may be convenient for the particular construction.

The subcircuit, generally designated by dotted lines at 20, comprising odds selector 10 and secondary selectors 12, 14, 16 and 18, may be included in a conventional game machine for either chance or home use. As shown in the drawing, the machine may include a power source 22, a disc or check operated switch 24 and a "win" indicator shown as a box at 26. Since these items are conventional, they are shown in schematic fashion.

Generally speaking, subcircuit 20 is wired so that odds selector 10 may be set from one pole to the next, and then to the next and so on, to include first one and then two, three and four secondary selectors respectively in series connection with the conventional circuitry of the game machine. Accordingly, the common terminal c of odds selector 10 is connected to one side of the conventional game circuit and at least one numbered terminal of secondary selector 12 is wired to the other side of the conventional game circuit. Each numbered pole of odds selector 10 is then wired to the common terminal c of one secondary selector. For example, pole number 2 of odds selector 10 is connected to the common c of secondary selector 14 and so on. Finally, at least one numbered pole of secondary selector 14 is connected to the common c of secondary selector 12, at least one numbered pole of secondary selector 16 is connected to the common c of secondary selector 14, and at least one numbered pole of secondary selector 18 is connected to the common c of secondary selector 16.

Thus, if odds selector 10 is turned to its pole number 1, a single secondary selector 12 will be in the series circuit. If odds selector 10 is turned to its pole numbered 2, two secondary selectors, 12 and 14, will be included in the series circuit. Similarly odds selector pole number 3 corresponds to three secondary selectors, 12, 14 and 16, in circuit, and so on through pole number 4.

OPERATION

The functioning of the above circuit may be best described by a discussion of the method of playing the game. The object of the game is to select the proper combination on the secondary selectors which will close the circuit and produce a win.

Accordingly, the player first selects the desired predetermined odds against which he wishes to play by setting the odds selector. The player then selects values for each secondary selector and places his disc or check in the slot. It will now become apparent why it is preferred that only one numbered pole of each secondary selector be "hot." Certainly the odds of selecting one "hot" pole from a multiple of "dead" poles will not be great. Further, it may be seen that as odds selector 10 is adjusted to include fewer or greater secondary selectors in the circuit, the odds of making the proper selection will be correspondingly greater or less.

If the player has selected the proper position for each secondary selector he will win. When his disc or check is placed in the slot, switch 24 will close and the win indicator 26 will be activated as in conventional devices.

Using the FIGURE as an example the player has set odds selector 10 to the number 3 position thus placing secondary selectors 12, 14 and 16 into the circuit. The player has also set secondary selectors 12, 14, 16 and 18 to pole positions 6, 3, 3 and 1 respectively. Of course, if the player should put his disc or check in the machine at this time he would lose since secondary selector 16 has not been properly set. If that selector had been set to pole position 2, or if odds selector 10 had been set to either of its lower values, however, the player would have won.

At this point it will be apparent that if a player should win once he will have determined the combination necessary to win every time. It is for this reason that the "hot" connections to the numbered poles of the secondary selectors are made to be changeable from one numbered pole to another. Thus periodically, or after a "win" has been recorded, the combination may be easily changed. The changeability of these connections may be provided in numerous ways, however, this invention is directed only to the basic electrical circuit, rather than the mechanical means for making this change, so those means need not be described in detail. Of course, one method would be to manually remove the connections and replace them in different locations. Another would be to provide each pole of each secondary selector with a switch between the pole and a "live" line. The switches could be manually activated or they could be operated by the insertion of a punched card into a card reading device. Further the entire switching sequence could be solid state and automatically activated by a win.

It has been previously stated that odds selector 10 may be set to choose among predetermined odds against a winning combination. There are four variables which determine those odds, as follows: (a) the

number of numbered poles on each secondary selector, (b) the number of such poles which are wired so as to be "hot" (c) the number of secondary selectors, and (d) the setting of the odds selector. It should be understood that any of these variables may be changed to suit the particular application and that any specification of those values, herein, or in the drawing, are for purposes of illustration only.

Many other alternative forms and arrangements of this invention will also be apparent from the above drawing and descriptions, however, these too are for purposes of illustration and none should be interpreted to limit the scope of the invention as claimed.

I claim:

1. A chance game device comprising an electric circuit including a power source and win indicator, the input of said electric circuit connected to the common terminal of a rotatable multiple pole odds switch, said poles being sequentially numbered; a plurality of rotatable multiple pole secondary switches in sequential order starting from a first, said poles of said secondary switches being numbered; the common terminal of each of said secondary switches taken in sequence each being connected to a respective one of said sequentially numbered poles of said odds switch; and all of said secondary switches taken in reverse sequence save said first having at least one but fewer than all of its numbered poles removably connected to the common terminal of the preceding secondary switch, with said first secondary switch having at least one but less than all of its numbered terminals removably connected to the output of said electric circuit, said power source and win indicator being connected in series between said output and input of said circuit.
